[57] CLAIM

The ornamental design for a compact, as shown and described.

DESCRIPTION

FIG. 1 is a perspective view of a compact embodying our new design;

FIG. 2 is a top plan view thereof;

FIG. 3 is a front elevational view thereof;

FIG. 4 is a rear elevational view thereof;

FIG. 5 is a bottom plan view thereof;

FIG. 6 is a right side elevational view thereof, the left side elevational view being the mirror image of the right side elevational view;

FIG. 7 is a perspective view of a second embodiment of a compact;

FIG. 8 is a top plan view of the compact of FIG. 7;

FIG. 9 is a front elevational view of the compact of FIG. 7;

FIG. 10 is a rear elevational view of the compact of FIG. 7;

FIG. 11 is a bottom plan view of the compact of FIG. 7; and,

FIG. 12 is a right side elevational view of the compact of FIG. 7, the left side elevational view being the mirror image of the right side elevational view.
